[57] **CLAIM**

The ornamental design for a vacuum panel container, as shown and described.

DESCRIPTION

FIG. 1 is a front elevational view of a vacuum panel container showing our new design, the rear elevation is the same except for the conventional screw threading on the neck;

FIG. 2 is top plan view;

FIG. 3 is a bottom plan view; and,

FIG. 4 is a fragmentary cross-sectional view taken along the lines 4—4 in FIG. 1.
